Primary Examiner — Cathron C Brooks*Assistant Examiner* — Sharon S Oum(74) *Attorney, Agent, or Firm* — McGarry Bair PC(57) **CLAIM**

The ornamental design for a combined ceiling fan motor housing and light fixture, as shown and described.

DESCRIPTION

FIG. 1 is a top perspective view of a combined ceiling fan motor housing and light fixture;

FIG. 2 is a bottom perspective view of the combined ceiling fan motor housing and light fixture of FIG. 1;

FIG. 3 is a top view of the combined ceiling fan motor housing and light fixture of FIG. 1;

FIG. 4 is a bottom view of the combined ceiling fan motor housing and light fixture of FIG. 1.

FIG. 5 is a right side view of the combined ceiling fan motor housing and light fixture of FIG. 1;

FIG. 6 is a left side view of the combined ceiling fan motor housing and light fixture of FIG. 1;

FIG. 7 is a front side view of the combined ceiling fan motor housing and light fixture of FIG. 1; and,

FIG. 8 is a rear side view of the combined ceiling fan motor housing and light fixture of FIG. 1.

The broken lines illustrate portions of the combined ceiling fan motor housing and light fixture that form no part of the claimed design.
